attorney.

UNITED STATES PATENT OFFICE.

ROBERT HARRY STEVENS, OF NEWARK, NEW JERSEY.

SANITARY CLOSURE FOR CONTAINERS.

1,252,194.

Specification of Letters Patent. Patented Jan. 1, 1918.

Application filed January 22, 1917. Serial No. 143,807.

To all whom it may concern:

Be it known that I, ROBERT H. STEVENS, a citizen of the United States, residing at Newark, in the county of Essex and State 5 of New Jersey, have invented a new and useful Sanitary Closure for Containers, of which the following is a specification.

This invention relates to closures for containers, or receptacles and is especially designed with reference to sanitary closures 10 for milk bottles. The invention is equally applicable to any form of container such as boxes or packages for liquids and material in powdered form.

15 The object of the invention is to provide a closure that will be perfectly sanitary and will prevent the milk from running down the side of the bottle.

A further object is to provide a closure 20 that will eliminate the necessity of removal of the ordinary closure, or milk cap, while pouring the contents of the bottle and while the bottle is being used for storage purposes.

In the accompanying drawings forming a 25 part of this specification,

Figure 1 is a top plan view of the applicant's closure.

Fig. 2 is a section taken on line X—X of Fig. 1.

30 Fig. 3 is a section similar to Fig 2 showing the lid in raised position.

Fig. 4 is a fragmental sectional view of the pouring spout showing the angular relation of the inner and outer beads.

35 The embodiment of applicant's invention illustrated in the attached drawings discloses two thicknesses of material used in constructing the body portions comprising the upper and lower sections 4 and 5. The 40 lower section is provided with the pouring orifice 7, ledge 8 and lip 10. The upper section is formed with a lid 12 having a projection, lip and lift when desired. Adjacent the rear of the orifice 7 the upper section is 45 adapted to be bent back forming a hinge joint 13. At the rear of the hinge joint the upper and lower sections are secured together in any suitable manner as by pasting.

When pressed into the annular groove 2 of the bottle the lower lip 10 forms a pouring ledge which effectually keeps the milk from flowing down the inside of the bottle. The upper lip perfectly covers the lower lip when in closed position thereby preventing any dirt or dust from coming in contact 50 with the pouring channel of the milk.

The pouring spout 10 is formed integral with the lower or closure member. This spout is angularly placed with respect to base member 5 and has its circumferential edge 60 bent over to an acute angle of greater degree than that on the corresponding edge of the closure flap thereby producing between the two members 10 and 12 sufficient friction and elasticity when in closed position to 65 function as a lock. The lip or flap member is provided with a bead or depression 9 to fit tightly inside the pouring aperture 7 in lower member to centrally place and aid in holding the closure flap in sealing position. 70

Centrally located on the overturned edge of the closure flap is provided a lifting tab 11 to be gripped by the fingers in operating the closure.

This invention is an improvement on the 75 invention set forth in my prior pending application, Serial Number 113,390, filed August 5, 1916.

What I claim is:—

In a closure the combination of a lower 80 member having a pouring orifice located within the circumferential limits of the member, an integral, angularly disposed circumferential pouring spout having an upper beaded edge, with an upper member having 85 a depressed portion to snugly engage the opening in lower member and a portion of said upper member being formed into a closure flap to completely cover the pouring spout when in closed position, and provided 90 with a circumferential bead to coact with bead on the pouring spout to form a fastener for the closure flap.

Jan. 6, 1917.

ROBERT HARRY STEVENS.
